DESIGN FOR A GLOVE

Camille V. Perrin, Grenoble, France, assignor to Perrin Glove Company, Inc., New York, N. Y., a corporation of New York

Application October 25, 1946, Serial No. 134,222

Term of patent 7 years

(Cl. D3—11)

To all whom it may concern:

Be it known that I, Camille V. Perrin, a citizen of the French Republic, residing at Grenoble, France, have invented a new, original, and ornamental Design for Gloves, of which the following is a specification, reference being had to the accompanying drawing, forming part thereof.

In said drawing:

I claim:

The ornamental design for a glove, as shown.
CAMILLE V. PERRIN.
